US00D833193S

(12) **United States Design Patent** (10) **Patent No.:** **US D833,193 S**
(45) **Date of Patent:** **** Nov. 13, 2018**

(54) **CHAIR**

(71) Applicant: **ARTCO-BELL CORPORATION**,
Temple, TX (US)

(72) Inventors: **David E. Mehaffey**, Muscatine, IA
(US); **Jeremy S. Rolfs**, Sylvan Lake,
MI (US)

(73) Assignee: **ARTCO-BELL CORPORATION**,
Temple, TX (US)

(**) Term: **15 Years**

(21) Appl. No.: **29/610,206**

(22) Filed: **Jul. 10, 2017**

Related U.S. Application Data

(63) Continuation of application No. 29/568,653, filed on Jun. 20, 2016, now Pat. No. Des. 796,883, which is a continuation of application No. 29/542,863, filed on Oct. 19, 2015, now Pat. No. Des. 759,414, which is a continuation of application No. 29/506,440, filed on Oct. 15, 2014, now Pat. No. Des. 743,180.

(57) **CLAIM**

The ornamental design for a chair, as shown and described.

DESCRIPTION

FIG. 1 is a perspective view of the chair from a first point of view.

FIG. 2 is a perspective view of the chair from a second point of view.

FIG. 3 is a front view of the chair.

FIG. 4 is a back view of the chair.

FIG. 5 is a right side view of the chair.

FIG. 6 is a left side view of the chair.

FIG. 7 is a top view of the chair; and,

FIG. 8 is a bottom view of the chair.

Broken lines are also for illustrative purposes only and form no part of the claimed design.

1 Claim, 8 Drawing Sheets
